DESIGN FOR A PRINTING PRESS

Curtis S. Crafts, Oak Park, Ill., assignor to The Goss Printing Press Company, Chicago, Ill., a corporation of Illinois

Application December 30, 1944, Serial No. 117,169

Term of patent 14 years

(Cl. D64—11)

To all whom it may concern:

Be it known that I, Curtis S. Crafts, a citizen of the United States of America, and resident of Oak Park, county of Cook, and State of Illinois, have invented a new, original, and ornamental Design for a Printing Press, of which the following is a specification, reference being had to the accompanying drawings, forming a part thereof.

Figure 3 is a front perspective view thereof, the rear of the printing press presenting substantially the same appearance as the front.

I claim:

The ornamental design for a printing press, as shown and described.

CURTIS S. CRAFTS.
